FORK OR THE LIKE

Robert J. King, Newburyport, Mass., assignor to Towle
Manufacturing Company, Newburyport, Mass., a corporation of Massachusetts

Application July 19, 1956, Serial No. 42,295

Term of patent 14 years

(Cl. D54—12)

FIG. 5

Fig. 1 is a front elevational view of a fork showing my new design;

Fig. 2 is a side elevation of Fig. 1;

Fig. 3 is a transverse section taken on the line 3—3 of Fig. 1;

Fig. 4 is a transverse section taken on the line 4—4 of Fig. 1; and

Fig. 5 is a back elevational view of the fork shown in Fig. 1.

I claim:

The ornamental design for a fork or the like, substantially as shown.
